PAUL J. MARKS, OF ROCHESTER, NEW YORK, ASSIGNOR TO EASTMAN KODAK COMPANY,
OF ROCHESTER, NEW YORK, A CORPORATION OF NEW YORK.

SHUTTER-ACTUATING DEVICE.

1,270,537.

Specification of Letters Patent. Patented June 25, 1918.

Application filed August 9, 1916. Serial No. 113,901.

To all whom it may concern:

Be it known that I, PAUL J. MARKS, of Rochester, in the county of Monroe and State of New York, have invented certain new and useful Improvements in Shutter-Actuating Devices; and I do hereby declare the following to be a full, clear, and exact description of the same, reference being had to the accompanying drawings, forming a part of this specification, and to the reference characters marked thereon.

My present invention relates to photography, and more particularly to actuating devices for setting off photographic shutters after the lapse of a timed interval when set by the operator, so that the latter may arrange himself in the field of the lens, for instance, and appear in the picture, and the invention has for its object to provide a simple, cheap and compact device of this character, that will be durable and efficient and act with certainty and precision. The improvements are directed in part toward providing a device particularly applicable to use on shutters equipped with cable releases, as distinguished from bulb releases. To these and other ends the invention consists in certain improvements and combinations of parts, all as will be hereinafter more fully described, the novel features being pointed out in the claims at the end of the specification.

In the drawings:

Figure 1 is a front elevation of a camera and shutter provided with an actuator constructed in accordance with and illustrating one embodiment of my invention;

Fig. 2 is a front view of the actuator detached;

Fig. 3 is a top or end view of the neck or coupling portion of the actuator, showing the clip for attaching it to the cable release, the said clip being in released position;

Fig. 4 is a view similar to Fig. 3, with the clip in operative position;

Fig. 5 is a detail section through the coupling portion of the actuator with the latter set for operation, the same being taken on the line 5—5 of Fig. 4;

Fig. 6 is a view similar to Fig. 5 with the parts represented during the operation of the actuator;

Fig. 7 is an interior view of the actuator

with the cover of the casing removed and the parts in normal position;

Fig. 8 is a view similar to Fig. 7 with the parts in set position;

Fig. 9 is a view similar to Fig. 8 with some of the overlying parts removed;

Fig. 10 is a fragmentary detail of part 60 of the retarding mechanism, and

Fig. 11 is a section taken substantially on the line 11—11 of Fig. 7.

Similar reference characters in the several figures indicate the same parts.

In the embodiment of the invention illustrated, the actuator is shown applied to a camera 1 having a shutter 2 of which 3 is the setting member, and 4 the operating or releasing member. The latter is depressed to trip the shutter by a thrust cable 5 within the tube 6 of a common form of shutter operating device known as a cable release. At its outer end the cable 5, or an inflexible extension 5^a thereof, carries a button or operating member 7, while the corresponding end of the tube 6 is similarly provided with a button or operating member 8 in which the operating member 7, or rather the extension 5^a, slides centrally. By pressing the button 7 inwardly, relatively to the button 8, the cable 5 is pushed against the operating member 4 of the shutter to release it, the button 8 being meanwhile held by counter pressure, so that the reaction of the cable movement is borne by the tube 6 against the shutter casing 2, and no vibration, due to thrust against the shutter structure as a whole, results, the forces being balanced. No further description of the cable release is believed to be necessary herein, as it is a well known device, and, so far as the present invention goes, merely performs the office of transmitting power to a suitable shutter part to cause the opening of the latter, and may be considered for certain purposes, and in certain aspects of the invention, as part of the shutter mechanism itself.

The requirements of the device of my invention, as shown in Fig. 2, are that it be applicable to apparatus above described and serve to operate the buttons 7 and 8 relatively, much as the thumb and fingers of the operator do when the shutter release is operated by hand and the button 8 held between

the fingers while the button 7 is pressed with the thumb. To these ends, the actuator possesses certain general features that I will first describe before going into its details 5 for convenience in obtaining an understanding of the device through an initial understanding of its use.

The device of the present embodiment consists of a two-part casing comprising a body 10 portion 9 (Figs. 2 and 11) and a disk shaped rotatable cover 10 therefor. The actuator is set by partially rotating the cover 10 by means of knobs 11 until an indicating mark 12 thereon moves to the right from the position of Fig. 2 to register with a neck 13 projecting from the casing. It is released by pressure on a button 14. The neck 13 referred to is threaded upon the outer projecting end of a small cylinder or tubular 15 guide 15 (Fig. 5) leading from the exterior to the interior of the casing. This tube or guide is adapted to receive the inner operating member or button 7 of the cable release, and in it operates a time controlled driving 20 member 16 adapted to engage the button 7. The other button 8 is coupled fixedly to the casing through being received in a seat 17 formed in the tube 15 or in the neck 13 thereon, which latter is provided with guiding 25 grooves or ways 18 slidably supporting a clip 19 (Figs. 3 and 4). After the button 8 is placed in the socket 17 the clip 19 is moved from the position of Fig. 3 to that of Fig. 4 to engage it and lock it in place.

35 After setting the actuator the cable release is applied with the parts disposed as shown in Fig. 5, and as the plate 10 revolves back to the position of Fig. 2 under the control of timing mechanism, hereinafter described, 40 the driver 16 is slowly thrust upwardly to the position of Fig. 6, carrying the button 7 with it and projecting the cable 5 to trip the shutter operating member 4.

I will now proceed with a description of 45 the timing mechanism contained within the casing, which brings about these results.

Referring more particularly to Fig. 9, 20 is the pivot of a one-piece lever 21 having a long arm 22 and a short arm 23. The 50 main spring 24 coiled about a stud 25 hooks over a pin 26 on the short arm 23 of the lever, and has a tendency to move it to the normal position of Fig. 7. A link 27 pivoted at 28 to the outer end of the long arm 55 22 carries at its other end the driver 16, before described, so that when the lever 21 is moved to the set position of Figs. 8 and 9 the driver is drawn outwardly in the guide 15 to admit the cable release button 7, and 60 when the lever is released the spring sends the driver back into the guide to the position of Fig. 6. The driver travels some distance together with the button 7 before the shutter lever 4 is actually tripped, and in 65 order to delay its travel and give the desired

time interval a retarding device is employed to act against the return movement of the lever 21 under the influence of the spring 24.

This retarding device consists, in the present embodiment, of a train of gears 29 70 driven by the lever 21 on its return movement, and the inertia of which supplies the resistance. A link 30 pivoted to the arm 22 at 31 carries a pin 32 that engages with one or another of two abutments 33 and 34 on 75 opposite sides of the pivot 35 of a gear segment 36, movable in two directions and meshing with a spur 37 (Fig. 10) on the shaft of one of the train of gears 29. The abutments 33 and 34 on the segment are 80 separated by a switch cam 38, and after each operation of the lever arm 22 and the attendant throw of the segment 36, the pin 32 on the link 30 is guided over to engagement with the other abutment of the segment on 85 the other side of the pivot under the influence of a spring arm 39 secured at 40 to the gear plate 41, this action occurring during the resetting of the lever 21 and winding of the spring 24. The spring 39 rests in a 90 notch or seat 42 (Fig. 11) in a plate 43 extending vertically on the segment 36 and its free end passes freely through a post 44 on the link 30. It will thus be understood that the gear train is driven in both directions 95 on alternate vibrations of the lever arm 22, and each movement of the train is therefore an effective retarding movement, no resetting of the train being required. The segment 36 simply swings in one direction with 100 one retardation, and in the other direction with the next.

There remains to be described the manner in which the rotation of the shutter cover 10 sets the lever arm 22 and winds the spring 105 24. The said cover 10 is pivoted on a boss 45 (Figs. 7, 8 and 11) on a bridge piece 46 spanning the body 9 of the casing. Adjacent to its pivot, it is provided with an inwardly projecting pin 47 coöperating with a slot 48 in the short arm 23 of the lever 21, so that as the disk or cover is rotated to the right in the figures, the lever 21 is moved from the normal position of Fig. 7 to the set position of Figs. 8 and 9. To hold the mechanism set, another pin 49, projecting from the under side of the cover plate near its margin, and which may be conveniently formed as an extension of one of the thumb pieces 11, engages behind a spring latch 50 110 secured at 51 to the casing or made part of the bridge piece 46. The releasing button 14 engages the latch 50 below the pin 49 to deflect it inwardly when pressed and release the said pin, permitting the time mechanism 120 to run down.

I claim as my invention:

1. In a shutter actuator, the combination with a time controlled mechanism of a casing for the time controlled mechanism com- 130

prising a body portion and a detachable disk shaped rotatable cover, the latter being adapted to set the time controlled mechanism when rotated on the body portion and being provided with a pin detachably coöperating with the slotted setting member when the cover is in place.

2. In a shutter actuator, the combination with a time controlled mechanism of a casing for the time controlled mechanism comprising a body portion and a disk shaped rotatable cover, the latter being adapted to set the time controlled mechanism when rotated on the body portion, and a latch cooperating with the cover to hold the time controlled mechanism set.

3. In a shutter actuator, the combination with a time controlled mechanism, a casing therefor having a tubular guide extending from the exterior to the interior thereof to receive the inner operating member of a cable release and having a socket at its exterior end adapted to receive the outer operating member thereof, said guide being provided with transverse guiding grooves in the region of the socket, a sliding clip movable in the grooves to interlock the said outer operating member and socket, and a plunger driven by the time controlled mechanism and operating in the tubular guide and adapted to engage and move the inner operating member.

4. In a shutter actuator, the combination with a casing, and means for coupling it to the controlling member of a shutter, of a time controlled mechanism in the casing embodying a guide in alinement with the coupling means, a driver movable therein, a lever, a main spring for vibrating the lever, a retarding device, a link for transmitting motion to the latter from the lever, and a link connecting the lever and driver.

5. In a shutter actuator, the combination with a casing comprising a body portion and a rotary cover, and means for coupling the body portion to the controlling member of a shutter, of a time controlled mechanism in the casing embodying a driver in alinement with the coupling means, a main

spring, a retarding device and a lever directly connected to the driver, the retarding device, the spring and the rotary cover of the casing.

6. In a shutter actuator, the combination with a casing and means for coupling it operatively to the controlling member of a shutter, of a time controlled mechanism in the casing embodying a tubular guide, a driving member movable therein, a lever extending transversely of the guide and having a long arm and a short arm, a main spring for vibrating the lever connected to act on the short arm thereof, a link connecting the long arm of the lever and the driving member and means coöperating with one of said lever arms to wind the main spring.

7. In a shutter actuator, the combination with a casing and means for coupling it operatively to the controlling member of a shutter, of a time controlled mechanism in the casing embodying a tubular guide, a driving member movable therein, a lever extending transversely of the guide and having a long arm and a short arm, a main spring for vibrating the lever connected to act on the short arm thereof, a link connecting the long arm of the lever and the driving member, a retarding device and a connection between the retarding device and the long arm of the lever.

8. In a shutter actuator, the combination with a casing and means for coupling it operatively to the controlling member of a shutter, of a time controlled mechanism in the casing embodying a tubular guide, a driving member movable therein, a lever extending transversely of the guide, a main spring for vibrating the lever, a link connecting the lever and the driving member, a gear train, a rocking segment meshing therewith and a link on the lever coöperating with the segment on first one and then the other side of its center on successive vibrations of the lever.
